UNITED STATES PATENT OFFICE.

JOSEPH A. GROEBLI, OF NEW YORK, N. Y.

EMBROIDERING MECHANISM.

1,398,590.

Specification of Letters Patent. Patented Nov. 29, 1921.

Application filed August 6, 1920. Serial No. 401,708.

To all whom it may concern:

Be it known that I, JOSEPH A. GROEBLI, a citizen of the United States, and resident of the city, county, and State of New York, 5 have invented certain new and useful Improvements in Embroidering Mechanism, of which the following is a specification.

My invention relates to that class of embroidery mechanism wherein tensioned 10 fabric is carried upon transferring means, such as rollers, mounted in a tambour frame, which may be shifted manually or automatically into successive stitch positions, the fabric being from time to time, automatically 15 slackened or untensioned, shifted forward, and tensioned, to present new portions of the fabric for the embroidering operation.

Automatic means for performing these successive steps of slackening, shifting and 20 tensioning are shown in my Letters Patent No. 1,247,264 of November 20, 1917, wherein such automatic means is applied to the control of the apparatus of one tambour frame.

The object of my present invention is to 25 provide means whereby the slackening, shifting, tensioning and other similar functions of the apparatus of the tambour frames of a plurality of embroidery machines may be governed by a single, common, and pref- 30 erably automatic, mechanism, thereby increasing the efficiency of such mechanism and avoiding the necessity of duplicating it for the several embroidery machines.

In the drawings, Figure 1 is a plan view 35 of mechanism governed from a common center and adapted to operate the mechanism of the tambour frames of a plurality of embroidery machines, the principal elements only of the governing mechanism being 40 shown, for clearness; Fig. 2 is a similar view, on an enlarged scale, of the governing mechanism and the connections for one tambour frame; Fig. 3 is an elevation, looking to the right on Fig. 2, the end of the driving 45 shaft and its connections being omitted for clearness; Fig. 4 is an elevation showing the connections for one tambour frame, taken on the line 4, 4 of Fig. 2, and Fig. 5 is a detail of one of the eccentrics and its strap.

50 In all the figures the same parts are designated by similar reference numerals.

The common governing mechanism may be similar to that shown in my aforementioned Patent No. 1,247,264. Thus, 26 indicates a motor, 27 and 28 connecting gears,

25 a driving shaft, carrying gears 29, 30, 48, 49, 64 and 65, adapted, through co-operating gears 31, 50 and 66, respectively, to rotate shafts 22, 20, 21, in either direction as may be required in carrying out the functions of the apparatus. These reference numerals designate the same parts in both my former Patent No. 1,247,264 and in the drawings herein. And, as the details of the mechanism for governing the direction, 60 sequence and extent of the rotation of the shafts 20, 21, 22 are fully described in my aforesaid patent, it is unnecessary to repeat that description, as the operation of the mechanism now to be described will be readily understood when it is borne in mind that the shafts 20, 21, 22 of the present invention are continuations of the shafts similarly numbered in my Patent No. 1,247,264.

Furthermore, the shaft 299 of the drawings represents a continuation of the shaft 299 of my Patent No. 1,247,264. And as the effect of its rotation upon the governing mechanism will be fully understood by reference to that patent, I have omitted the details of that governing mechanism from the present drawings.

The shaft 20 actuates the lateral tensioning mechanism of the several tambour frames. To accomplish this it is extended 85 through a suitable bearing 40, in a bracket 39, attached to frame 38 of each embroidery machine, and is provided with a plurality of spiral gears 41, 41, each adapted to mesh with a spiral gear 42, carried upon a 90 shaft 43, supported at one end by a bell crank 44 pivoted in the bracket 39, and adapted to be rocked by a pitman rod 45, so as to throw the gears 42 and 41 into and out of mesh.

The other end of each shaft 43 is carried by a suitable bearing 46 on the bracket 39, and, through the knuckle joint 47, shaft 52, sleeve 53, shaft 54, and knuckle 55, or other suitable flexible connections, turns the shaft 100 8 which corresponds to the shaft 8 of my said Patent No. 1,247,264, and operates mechanism like that described in that patent, to release and to apply lateral tension to the fabric, as called for in the operation of the 105 machine.

The shaft 21 actuates the vertical tensioning mechanism. To accomplish this it is extended through a suitable bearing 60 in the bracket 39 of each embroidery machine,

and is provided with a plurality of spiral gears 61, 61, each adapted to mesh with a spiral gear 62 carried upon a shaft 63, supported at one end by a bell crank 67, pivoted in the bracket 39 and adapted to be rocked by the pitman rod 145 so as to throw the spiral gears 62 and 61 into and out of mesh.

The other end of each shaft 65 is carried by a suitable bearing 68 in the bracket 39, 10 and, through the knuckle joint 69, shaft 70, sleeve 71, shaft 72, and knuckle 73, or other suitable, flexible connections, turns the shaft 9 which corresponds to the shaft 9 of my said Patent No. 1,247,264 and operates 15 mechanism like that described in that patent, to release and to apply vertical tension as called for in the operation of each machine.

The shaft 22 actuates the fabric shifting 20 mechanism. To accomplish this it is extended through a suitable bearing 80 in the bracket 39 of each embroidering machine, and is provided with a plurality of spiral gears 81, 81, each adapted to mesh with a 25 spiral gear 82, carried upon a shaft 83, supported at one end by a bell crank 84 pivoted in the bracket 39 and adapted to be rocked by the pitman rod 245 so as to throw the gears 82 and 81 into and out of mesh.

30 The other end of the shaft 83 is carried by a suitable bearing 84 in the bracket 39, and, through knuckle joint 85, shaft 86, sleeve 87, shaft 88 and knuckle joint 89, or other suitable flexible connections, turns the 35 shaft 10 which corresponds to the shaft 10 of my said Patent No. 1,247,264, and operates mechanism like that described in that patent to shift the fabric as called for in the operation of each machine.

40 The shaft 299 governs the extent of the shifting movement of the fabric.

To accomplish this it is extended through a suitable bearing 90 in the bracket 39 of each embroidering machine, and is provided 45 with a plurality of spiral gears 91, 91, each adapted to mesh with a spiral gear 92, carried upon a shaft 93, supported at one end by a bell crank 94, adapted to be rocked by the pitman rod 345, so as to throw the 50 gears 92 and 91 into and out of mesh.

The other end of the shaft 93 is carried by a suitable bearing 94, in the bracket 39, and, through the knuckle joint 95, shaft 96, sleeve 97, shaft 98, and knuckle 99, is turned 55 by the shaft 214 which corresponds to the shaft 214 of my said Patent No. 1,247,264, and operates, as described in that patent, to govern the extent of the shifting movement of the fabric as called for in the operation 60 of each embroidering machine.

65 Mounted in suitable bearings 100, 101 in each of the brackets 39, is a shaft 102, provided with a crank handle 103, by which it may be rotated, and carrying eccentric cams 104, 105, 106 and 107, which are indicated

by broken lines in Fig. 2, a side view of the cam 104 being shown in Fig. 3, and the other three cams being similar thereto. These cams coöperate with the straps 114, 115, 116 and 117 on the respective pitman 70 rods 45, 145, 245, 345, so that, when the shaft 102 is turned, the movement of its cams will rock the pitman rods and their respective bell cranks causing the latter to raise the shafts 43, 63, 83, 93, so as to mesh 75 their respective spiral gears 42, 62, 82, 92, with their coöperating spiral gears 41, 61, 81, 91, or to lower the shafts and separate the gears, as may be desired.

Normally, the tensioning and shifting 80 mechanism for each tambour frame is disconnected from the common governing mechanism, the spiral gears 42, 62, 82, 92 being out of mesh with their coöperating gears 41, 61, 81, 91.

85 However, whenever it is desired to untension, shift and retention the fabric of either tambour frame, by turning the hand crank 103 the spiral gears 42, 62, 82, 92 may be made to mesh with the gears 41, 61, 90 81, 91, thus connecting the tensioning and shifting mechanism of that tambour frame with the common governing mechanism, through the shafts 20, 21, 22 and 299.

90 That governing mechanism may then be caused to function, under the influence of the motor 26, so that the various steps of releasing the lateral tension, releasing the vertical tension, shifting the fabric, applying the vertical tension and applying the 100 lateral tension will be carried out, automatically, as described in my Patent No. 1,247,264.

95 Obviously, also, the mechanism of several of the tambour frames may be connected 105 with the common governing mechanism, as above described, so that the several operations of releasing the tension, shifting the fabric, and reapplying tension thereto may be carried out simultaneously on the several 110 tambour frames, thus permitting one common governing mechanism to function for one or for a plurality of separate tambour frames so that the operations will be carried out as satisfactorily and efficiently for each 115 tambour frame as would be the case if each were provided with an independent governing mechanism.

120 To insure accuracy of operation in meshing and disconnecting the gears, through the rotation of the shaft 102, it is preferable to provide means such as an arm 108 on the cam 104, and stops 109 and 110 on the bracket 39 which will limit the movement of the shaft 102 to a half revolution.

125 It will be understood, also, by those familiar with the art, that the sleeves 71, 53, 87 and 97 are telescoping sleeves which permit the rotation of the rods which they respectively connect and also the lengthening 130

and shortening of the connections between those rods to compensate for the movements of the tambour frame.

The form of mechanism shown in the drawings is intended to illustrate a type of construction by which my improvements may be carried out in practice. And it will be readily appreciated, by those familiar with the art, that details of the construction may be modified, as by the use of mechanical equivalents and the like, without departing from the spirit of my invention or the scope of the claims.

Having thus described my invention what I claim and desire to secure by Letters Patent of the United States is:—

1. In embroidering mechanism, the combination, with a plurality of embroidering machines, each embodying fabric carrying, shifting and tensioning means, of common means for controlling the operation of the shifting and tensioning means to shift and tension the fabric on the carrying means of each and optionally of a plurality of the several embroidering machines.

2. In embroidering mechanism, the combination, with a plurality of embroidering machines, each embodying fabric carrying, shifting and tensioning means, of common, automatic means for controlling the operation of the shifting and tensioning means to shift and tension the fabric on the carrying means of the several embroidering machines both separately and simultaneously.

3. In embroidering mechanism, the combination, with a plurality of embroidering machines, each embodying fabric carrying, shifting and tensioning means, of common means for controlling the operation of the shifting and tensioning means to shift and tension the fabric on the carrying means of the several embroidering machines both separately and simultaneously.

4. In embroidering mechanism, the combination, with a plurality of embroidering machines, each embodying tambour frames provided with fabric shifting and tensioning means, of common means for controlling the operation of the shifting and tensioning means to shift and tension the fabric on the tambour frames of the several embroidering machines both separately and simultaneously.

5. In embroidering mechanism, the combination, with a plurality of embroidering machines, each embodying fabric carrying,

shifting and tensioning means, of common means for controlling the operation of the shifting and tensioning means to shift and tension the fabric on the carrying means of the several embroidering machines, and means for bringing the shifting and tensioning means of each embroidering machine optionally under the control of said common means.

6. In embroidering mechanism, the combination, with a plurality of embroidering machines, each embodying fabric carrying, shifting and tensioning means, of common means for controlling the operation of the shifting and tensioning means to shift and tension the fabric on the carrying means of the several embroidering machines, and means for simultaneously bringing the shifting and tensioning means of each of selective pluralities of such embroidering machines under the control of said common means.

7. In embroidering mechanism, the combination, with a plurality of embroidering machines, each embodying fabric carrying means, and means for performing a plurality of functions in the shifting and tensioning of a fabric on the carrying means, of common means for controlling the sequence and extent of the carrying out of such functions of the embroidering machines separately and optionally concurrently.

8. In embroidering mechanism, the combination, with a plurality of embroidering machines, each embodying fabric carrying means, and means for performing a plurality of functions in the shifting and tensioning of a fabric on the carrying means, of common means for controlling the sequence and extent of the carrying out of such functions of each embroidering machine independently and of either of several selective pluralities of such machines concurrently.

9. In embroidering mechanism, the combination, with a plurality of embroidering machines, each embodying fabric carrying means, and means for performing a plurality of functions in the shifting and tensioning of a fabric on the carrying means, of common, automatic means for controlling the sequence and extent of the carrying out of such functions of the embroidering machines separately and optionally concurrently.

JOSEPH A. GROEBLI.
